UNITED STATES PATENT OFFICE

148,009

DESIGN FOR A TABLE LAMP

Robert L. Dean, El Cerrito, Calif.

Application August 19, 1946, Serial No. 132,663

Term of patent 7 years

(Cl. D48—20)

To all whom it may concern:

Be it known that I, Robert L. Dean, a citizen of the United States, residing at El Cerrito, in the county of Contra Costa and State of California, have invented a new, original, and ornamental Design for Table Lamps, of which the following is a specification, reference being had to the accompanying drawing, forming a part thereof.

Fig. 1 is a side elevation of a table lamp, showing my new design.

Fig. 2 is a top plan view of Fig. 1 with lamp socket removed.

The characteristic features of my design reside in the portions shown in full lines.

I claim:

The ornamental design for a table lamp, as shown and described.

ROBERT L. DEAN.
